UNITED STATES PATENT OFFICE.

GLENN ADAMS, OF CINCINNATI, OHIO.

DESIGN FOR A BADGE, EMBLEM, OR SIMILAR ARTICLE.

47,707.

Specification for Design.

Patented Aug. 17, 1915.

Application filed April 4, 1912. Serial No. 688,551. Term of patent 14 years.

To all whom it may concern:

Be it known that I, GLENN ADAMS, a citizen of the United States, residing at Cincinnati, in the county of Hamilton and State of Ohio, have invented a new, original, and ornamental Design for a Badge, Emblem, or Similar Article, of which the following is a specification.

The accompanying drawing is a plan view of a badge, emblem, or similar article, having my design, comprising the representation of a bear with the letters F O B extending across the same, applied thereto.

I claim:—

The ornamental design for a badge, emblem, or similar article, as shown.

In testimony whereof I affix my signature in presence of two witnesses.

GLENN ADAMS.
